DESIGN FOR A ROOFING

Norman P. Harshberger, Scarsdale, N. Y., assignor to Bakelite Building Products Co. Inc., New York, N. Y., a corporation of Delaware

Application August 24, 1934, Serial No. 53,039

Term of patent 14 years

To all whom it may concern:

Be it known that I, Norman P. Harshberger, a citizen of the United States, residing at Scarsdale, in the county of Westchester and State of New York, have invented a new, original, and ornamental Design for Roofing, of which the following is a specification, reference being had to the accompanying drawing, forming part thereof.

In the drawing, Fig. 1 is a plan view of the

roofing showing my new design forming a distinctive random effect, the ends being broken away, and

Fig. 2 is a section taken at 2—2 in Fig. 1 showing the manner in which the roofing elements in Fig. 1 are laid.

I claim:

The ornamental design for a roofing substantially as shown and described.

NORMAN P. HARSHBERGER.
